[57] CLAIM

The ornamental design for a door display, unit as shown and described.

DESCRIPTION

FIG. 1 is a perspective view of a door display unit; FIG. 2 is a plan view of the door display unit with doors shown in phantom mounted on the display unit, the doors not being integral parts of the display unit; FIG. 3 is a front view with the doors shown in phantom;

FIG. 4 is a bottom view of the door display unit; FIG. 5 is a plan view of the unit; FIG. 6 is a front view of the unit; FIG. 7 is a right side elevation view the left side being the same in appearance; and, FIG. 8 is a cross-sectional view taken on the line 8—8 in FIG. 7.

The broken line showings in FIGS. 2 and 3 are for illustrative purposes only and form no part of the claimed design.

FIG. 2

FIG. 1
